Inventor:

FRANK L. CASPER,

by William N. Dow,

Attorney.

UNITED STATES PATENT OFFICE.

FRANK L. CASPER, OF HOWE'S CAVE, NEW YORK.

TABLE-LEAF SUPPORT.

SPECIFICATION forming part of Letters Patent No. 373,813, dated November 29, 1887.

Application filed August 25, 1887. Serial No. 247,826. (No model.)

To all whom it may concern:

Be it known that I, FRANK L. CASPER, of Howe's Cave, in the county of Schoharie and State of New York, have invented new and useful Improvements in Table-Leaf Supports, of which the following is a specification.

My invention relates to improvements in table-leaf-supporting attachments; and the object of my invention is to provide a simple and effective device for that purpose. This object I attain by the mechanism illustrated in the accompanying drawings, which are herein referred to and form part of this specification, and in which—

15 Figure 1 is a vertical section of part of a table provided with my invention, showing the leaf raised and my support in side elevation; Fig. 2, a like section with the leaf shown in a hanging position; Fig. 3, a front elevation of Fig. 1; Fig. 4, a transverse section of Fig. 1 at the line X-X; and Figs. 5, 6, and 7 are enlarged and detached details of the separate parts of my support.

As represented in the drawings, A indicates 25 the table-top, B a leaf hinged to said top, and C the frame-work of the table. All of said parts are of an old and well-known construction and form no part of my invention.

D is rolling brace-bar having at one end a 30 spring-limb, 1, which is provided with a locking-shoulder, 2, near its free end. Said brace is also provided on its end near said spring-limb with a button-head, 3, and at the opposite end with a journal, 4, and a crank-handle, 35 5, by which a rolling motion can be imparted to said brace. The normal position of the latter is one where the spring-limb will lie directly above the body of the brace, as shown in Fig. 1.

40 E is a looped hanger which is secured to the under side of the leaf B, and in which the journal 4 of the brace D is fitted, so that said brace will be securely attached to the leaf thereby, but will be free to receive a rolling motion and a slight pendulous movement 45 therein. Said hanger is provided with a spur or stop, 6, against which the crank-handle 5 engages to prevent the brace D from being rolled too far in that direction.

50 F is a bracket (shown in vertical section in Fig. 1) which is secured to the frame C, and has a rearwardly-inclined portion, f, provided

with a parallel slot, 7, that is closed at its lower end to form a loop in which the brace-bar D will slide endwise. Said slot is extended upwardly in the plate of the bracket, and is there increased in size at one side by the curved enlargement 8 for the purpose of permitting the spring-limb of the brace-bar to pass freely therethrough in the operation of 60 disengaging the support. A catch-piece, 9, is formed in the upper end of the enlargement of the opening, for the purpose of providing a striker with which the shoulder 2 of the brace-bar will engage to lock the support for 65 holding the leaf B in its raised position, as shown in Fig. 1.

The operation of my device is as follows: The leaf B being in a pendent position, as shown in Fig. 2, in raising said leaf the brace-bar D will thereby be drawn endwise through the slotted opening of the bracket F, in which movement the button-head 3 will prevent said brace-bar from escaping from said opening, and will also prevent the leaf B from being 75 raised too high, and when the rising movement of said leaf is nearly completed the lower edge of the catch-piece 9 will press the spring-limb 1 downward until the shoulder 2 has passed under said catch-piece, and then the 80 resilience of said spring-limb will instantly cause it to resume its normal position, and thereby the shoulder 2 will be engaged with the face of the catch-piece 9 to lock the device to support the leaf B in its raised position, as 85 shown in Fig. 1. To lower the leaf B the brace-bar D must be rolled by means of the crank-handle 5 until the shoulder 2 is clear from the catch-piece 9, as indicated by dotted circles in Fig. 4. Thereupon the brace-bar D 90 will freely slide inwardly through the slotted opening of the bracket F until the parts are returned to the positions shown in Fig. 2.

I claim as my invention—

1. In a table-leaf support, the combination 95 of a rolling brace-bar provided with a spring-limb having a locking-shoulder, as herein described, a looped hanger in which said brace-bar is journaled to the table-leaf, and a slotted bracket provided with a catch-piece with 100 which the shoulder of the spring-limb engages, as herein set forth, the rolling movement of said brace-bar producing the unlocking of the device, as herein specified.

2. A table-leaf support consisting of a rolling brace-bar, D, provided with a crank-handle and a spring-limb having a locking-shoulder, a looped hanger, E, by which said brace-bar is journaled to the table-leaf, and a bracket, F, provided with a slotted opening which is enlarged at one side near its upper end, and having a catch-piece at its upper end with which the shoulder of the spring-limb engages, and from which said shoulder is disengaged by the rolling movement of the brace-bar, as specified.
